UNITED STATES PATENT OFFICE.

CHARLES T. LIBBY, OF PORTLAND, MAINE.

LINOTYPE-MACHINE.

No. 832,398.

Specification of Letters Patent.

Patented Oct. 2, 1906.

Application filed July 23, 1903. Serial No. 166,651.

To all whom it may concern:

Be it known that I, CHARLES T. LIBBY, a citizen of the United States, residing at Portland, in the county of Cumberland and State of Maine, have invented certain new and useful Improvements in Linotype-Machines; and I do hereby declare the following to be a clear, full, and exact description of the invention, such as will enable others skilled in the art to which it appertains to make and use the same.

This invention relates to improvements in machines of the general character of the so-called "Mergenthaler" linotype-machine shown and described in Letters Patent of the United States No. 436,532, dated September 16, 1890.

It relates to means for reciprocating the assembling-elevator by automatic actuating mechanism set in motion by the operator each time it acts.

It also relates to means for reciprocating the assembling-elevator by automatic actuating mechanism that runs continuously and independently of the operator.

It also relates to means for changing the machine from the former class to the latter and back again.

It also relates to means for controlling the automatic-actuated mechanism and for bringing it into action at the will of the operator.

It also relates to certain details of construction hereinafter described and specifically explained.

The existing machine is started by the line-delivery carriage being released by the putting up of the assembling-elevator, which the operator does by a hand-lever each time he has assembled a matrix-line, and the machine automatically stops after casting the line thus sent up unless the next line has already been sent up, in which case the start-and-stop mechanism of the machine is thrown out and its main driving-shaft instead of stopping runs continuously. By my improved mechanism the assembling-elevator is put up automatically and is either set in operation by the operator each time he has assembled a matrix-line or at his option the line-delivery-carriage shaft on its return through intermediate mechanism starts the assembling-elevator, thus making the machine constant running irrespective of the operator.

In the drawings herewith accompanying

and forming a part of this application, Figure 1 is a perspective view of a portion of the Mergenthaler machine, showing my improvements applied thereto, the position of the several parts being that which they occupy at the instant the assembling-elevator releases the line-delivery carriage. Fig. 2 is a similar view from another position. Fig. 3 is a plan view of the two rods, bracket, key-lever, cam, &c. Fig. 4 is a detail elevation view showing the latch and back rod with their connections. Fig. 5 is a detail sectional view of the device for adjusting the tension-spring of the forked lever. Fig. 6 is a plan view of the frictional driving mechanism, and Fig. 7 is a vertical sectional view taken immediately in front of rod 14.

Same reference characters refer to like parts.

In said drawings, A represents the base; B, the front of the frame; C, the line-delivery carriage; D, the line-delivery-carriage lever; E, the line-delivery-carriage shaft; F, the assembling-elevator; G, the keyboard; H, a pivoted latch for retaining the line-delivery carriage; I, the line-delivery-carriage-releasing pin; J, the needle on the assembling-elevator for operating said releasing-pin; K, the hook for supporting the assembling-elevator; L, the assembling-elevator-releasing bar; M, the assembling-elevator lever, and N the assembling-elevator-lever link; O, the assembling-elevator counter-balancing-spring, and P the keyboard-driving shaft. These parts may be substantially the same and operate in substantially the same manner as in the aforesaid Mergenthaler machine.

In carrying out my invention I substitute for the handle on the right-hand end of the assembling-elevator lever and attach rigidly thereto a friction-disk 1. In the end of the lever I fix a stud 2, on which I place a counterpart friction-disk 3, made part of a pulley and driven constantly by a belt 4 from a grooved hub 5 on the shaft used to drive the keyboard connections, as in the existing machine. The disk-face I make of large diameter for the sake of greater efficiency, and the neck or hub between the disk portion and the pulley end I make small to adapt it to the forked lever herein-after described. In the end of the stud I place a cap-screw 6, with a head large enough to keep the friction-disk from coming off and allowing just play enough on the

stud to permit of throwing the friction-disks out of action. On the right-hand end of the keyboard I mount a bracket 7, carrying a vertical stud 8, and on this stud I place a loose two-ended lever 9, forked at one end and adapted to engage the counterpart friction-disk, the other end having its top edge square-cornered, so as to be nicely held by the angles of the two rods described below. I attach to the forked lever two spiral springs 10 10^a, one on each side of its stud and both anchored to the keyboard. The front spring 10 I make minutely adjustable by means of a nut 11, having a notched disk held at any desired point by a flatspring 12, screwed to the top edge of the lever and adapted to fit into the notches, this nut working on a threaded hook 13, passing through a plain hole in the lever, with the spring hooked thereon. The strength of these two springs I adjust so that the front one is slightly more efficient than the back one, the difference being just enough to make the friction-disks bite enough to raise the assembling-elevator and at the end of the trip bring back the front rod, as hereinafter described. When thus adjusted, the slightest obstruction or the weight of the operator's hand on the assembling-elevator is sufficient to make the friction-disks slip until the obstruction is removed.

As an aid to lightness of movement and for additional adjustment to the weight of different-length matrix-lines I retain the assembling-elevator balancing-spring and its connections as in the existing machine, only attaching it to the assembling-elevator-lever shaft at a shorter radius, so as to have its tension more uniform over the different positions of the assembling-elevator and making it stronger, so as not to reduce its efficiency when I reduce its working radius.

Through the keyboard, back of the space-band bar and above the space-band lever, I extend right and left two rods 14 15, partly resting in their holes through the sides of the keyboard and partly supported by spiral springs, two each, all anchored to the top edges of the keyboard sides, the front-rod springs 16 16 extending from their anchorage downward and leftward to their points of attachment to the rod and having strength enough only to promptly shift the front rod to the right when released by the key-lever below mentioned, the back-rod springs 17 17 extending from their anchorage downward and rightward to their points of attachment to the rod and having strength enough not merely to shift the back rod to the left, but also to pull the back end of the forked lever to the left against the preponderate force of its tension-spring. The right-hand end of both rods I bend downward in a right-angled hook and arrange them to hook over the top edge of the back

end of the forked lever. The left-hand ends of the two rods are adapted to be operated the front one by a key-lever, the back one by the line-delivery shaft, as below described.

The left-hand end of the back rod I bend at slightly less than right angles, reaching upward and slightly backward, so as to engage an eccentric screw 18, which I place on the end of the line-delivery shaft or hub of the line-delivery lever, on the top edge and slightly to the left of the center when the shaft is in its rightward position, so that the last rightward movement of the stud will rise slightly and lightly push the back rod to the right when the eccentric screw engages the rod. The eccentric screw should be adjusted to let the forked lever free just as the line-delivery carriage arrives back. The eccentric screw may be provided with a flange 19 on its front edge, behind which flange may pass a spur 20 of the back rod to keep it from canting.

The left-hand end of the front rod I arrange to rest lightly on top of the bracket below mentioned, and on the top of the rod I cut a notch 14^a, adapted to be engaged by the back end of the key-lever 21, pivotally mounted on the bracket, the front end reaching to a point convenient to be touched and pressed down by the operator. The back end of the key-lever is provided with a spring 22, tending to pull it down into its notch in the front rod. Also at the left end I place two spurs, one, 23, reaching up, where the operator can conveniently push it to the left, and thereby throw off the power and latch the front rod over in any emergency, the other, 24, reaching downward and beveled downwardly and leftwardly, the face of the bevel adjusted to lie in the path of an extension 25, which I place on the assembling-elevator lever when the front rod is to the right. The extension I fasten to the lever by set-screws in slotted holes, so that the extension can be adjusted upward or downward to the point that will throw off the friction-disks just as the assembling-elevator arrives up. A pin 26 through the front rod to the left of the keyboard is adjusted to prevent the rod and its bevel face passing too far to the right.

The bracket 27, which fastens to the frame of the machine, preferably having an arm at the bottom end reaching to the right, so as to fasten by the same screws that hold the keyboard in place, is provided with a spur 28, reaching downward, opposite and to the right of the beveled spur on the front rod, so placed that as the extension goes up it passes parallel with and close to it, and thus is adapted to take the side thrust and insure uniform action when the extension engages the bevel face and forces the front rod back to the left. A similar spur 29, reaching upward to the right of the back end of the key-lever and close to it, is adapted to take the pull of the

springs when the front rod is latched to the left.

Pivots mounted on the bracket I place a clasp 30, working at right angles to the key-lever and adapted to lock the front end of the key-lever down.

On the frame of the machine to the left of the assembling-elevator I pivotally mount a latch 47, adapted to latch under a corner of the assembling-elevator when in its higher position and hold it up. Above said latch I place a flat spring 48, tending to hold said latch in engagement. Near the bottom of the frame I pivotally mount a lever 49, with one end adapted to engage said latch adversely to said spring, the other end carrying an antifriction-roll 50, engaging a cam 51, which I place on the end of the line-delivery shaft. The arm of the lever carrying the roll is offset backward and leftward in order to bring it into a working relation with said shaft. Said cam I make with two faces, one adapted to hold the latch clear of the elevator, the other to hold it from turning too far under the elevator. The step between these two faces I place so as to act at the moment when the line of matrices has passed clear of the elevator. This device is additional to the assembling-elevator hook on the existing machine, which I add by reason of the liability of the latter to slip off.

The machine thus constructed may be operated in three ways: First, when the operator touches the key every time a line is ready. In this case the machine is in ready position when the front rod is latched to the left, the back rod held to the right by the eccentric screw, the elevator staying down by gravity, the friction-disks apart, held apart by the front rod. The operator touching the key when his line is ready raises the back end of the key-lever, which releases the front rod and that in turn releases the forked lever, which thereupon presses the friction-disks together, carrying the elevator up. As the elevator reaches its upward limit the needle J hits the movable pin in the line-delivery carriage, which in turn engages and raises the line-delivery-carriage latch, releasing it. At the same instant the extension on the assembling-elevator lever comes to bearing between the beveled lug on the front rod and the straight lug on the bracket, thereby forcing the front rod to the left and letting the friction-disks apart. The elevator stays up supported by its latch and hook until the line of matrices has passed out of it. At this point the releasing-bar knocks off the assembling-elevator hook and the cam throws out its latch, releasing the assembling-elevator, which falls by gravity, its fall broken by its balancing-spring, as in the existing machine. The eccentric screw is passing an idle course with the back rod left free, which thereupon is pulled to the left by its springs engaging the

forked lever. The forked lever is now held by both rods, for when the front rod was forced to the left by the extension on the assembling-elevator lever the key-lever dropped into its notch, latching it. As the line-delivery shaft returns, the eccentric screw engages the back rod, pushing it to the right and leaving the forked lever held only by the front rod. All parts are now again in ready position.

The second method of operation is when the operator hits the key before the line-delivery carriage gets back. At such time the back rod is to the left and holding the friction-disks apart, as the eccentric screw is away from the back rod. The operator touches the key, raising the back end of the key-lever. The front rod springs to the right; but the friction-disks remain apart, held apart by the back rod. This situation continues until the line-delivery shaft returns. The eccentric screw then engages the back rod, forcing it to the right and the elevator starts up. The situation now is the same as if the elevator had been released by touching the key with the line-delivery shaft back.

The third method of operation is when the key-lever is locked out, thereby leaving the front rod idle to the right, except when the assembling-elevator-lever extension holds it to the left. When the elevator starts down, the elevator-lever extension passes down and the front rod passes to the right immediately, not being latched by the key-lever, which is locked out. This leaves the friction-disk controlled only by the back rod. The operation under this condition resembles the second method, as each return of the line-delivery shaft presses the friction-disks together, leaving the burden on the operator to have his line ready to go up in readiness for that. If bad copy or other interruption prevents such readiness, the operator releases the key-lever, thereby bringing the front rod again into action, by which step an instant change is effected.

The scope of this application, generally speaking, is (1) friction-disk adapted to raise the assembling-elevator; (2) varying form of my devices for coördinating the elevator-raising mechanism to the general machine movements adapted to mechanism driven from a constantly-rotating pulley; (3) varying form of my double-controlling devices adapted like 2; (4) device for elevator-raising mechanism driven from a constantly-rotating pulley adapted to disconnect it when the elevator has been raised; (5) varying form of device for locking the elevator up until cleared by the matrix-line. Any equivalent means which may be substituted for the specific devices herein shown for these purposes, all of which are equally within the spirit and scope of my invention and likewise the aux-

illary mechanism for regulating and controlling the main features of my invention may be greatly varied, and I desire not to be limited in these respects otherwise than as specifically set out in the claims.

The advantages of my improved machine are as follows: It is optional with the operator to have it either a constant-running or a start-and-stop machine. The former method is valuable to the large number of operators who are able to set news-measure to the full speed of the machine and who are thus saved the labor and nervous strain of putting up the assembling-elevator and watching the movement of the machine for the proper time of doing so, in fact having nothing left to do but to be sure their line is set before the elevator goes up and then enjoying an instant's relaxation and an opportunity to glance at copy while the assembling-elevator automatically goes up and returns. Furthermore, operators who are otherwise unable to set lines to the full speed of the machine will have their speed increased, because my improved machine will save all interruption of their attention to copy caused by using the hand-lever to put up the assembling-elevator and the time while the elevator is passing up and back will enable them to be all ready to set the next line immediately the elevator is returned. Upon any interruption in completing a line of matrices the operator may instantly change the machine to the start-and-stop form by throwing off the clasp.

Having thus described my invention and its use, I claim—

1. In a linotype-machine, the combination of an assembling-elevator, devices for raising the assembling-elevator, devices for connecting the assembling-elevator with power mechanism, a device for automatically disconnecting the elevator from the power mechanism, and a counter device for regulating the return movement of the elevator.

2. In a linotype-machine, the combination of an assembling-elevator, devices for raising the assembling-elevator, devices for connecting the assembling-elevator with power mechanism, a device for setting the elevating apparatus in operation, a device for automatically disconnecting the elevator from the power mechanism.

3. In a linotype-machine, in combination with a movable assembling-elevator, mechanism adapted when connected with power to raise said elevator and when disconnected to let it fall, and means for connecting and disconnecting said raising mechanism.

4. In a linotype-machine, in combination with a movable assembling-elevator, means for raising same and devices for disconnecting the power from said raising means adapted to act after the elevator has been raised and in time to permit its return by gravity.

5. In a linotype-machine, the combination of the assembling-elevator, devices for raising the elevator having power mechanism connected with the power mechanism of the machine, a trigger adapted to set the power mechanism of the elevating device in operation and devices for automatically disconnecting the power devices of the elevator-raising mechanism.

6. In a linotype-machine, in combination with the movable assembling-elevator, disconnectible mechanism for automatically raising the same and means for disconnecting it before the elevator begins to descend.

7. In a linotype-machine, an assembling-elevator, elevator-raising mechanism comprising a source of power and intermediate connecting mechanism, a make-and-break connection in said intermediate mechanism, and means for automatically making said connection and means for breaking said connection while the elevator is up.

8. In a linotype-machine, the movable assembling-elevator, its lever-shaft and link, in combination with a friction-disk, power-driven, adapted to actuate said elevator.

9. In a linotype-machine, in combination, the assembling-elevator, adapted to have a reciprocating movement, automatic means for raising said elevator, means for disconnecting the raising means so as to permit said elevator to return by gravity, and means for reengaging said raising means when said elevator is again ready to be raised.

10. In a linotype-machine, in combination, the assembling-elevator, automatic elevator-raising mechanism and means for disconnecting the latter allowing the former to fall by gravity.

11. In a linotype-machine, in combination, the vertically-movable assembling-elevator, separable power-driven devices for raising same, spring-tensioned devices tending to hold the parts of the raising devices in operative contact, a device adapted automatically to periodically overpower the last-named devices and separate the parts of the power-driven devices, a key adapted to automatically hold the last-named device in overpowering position and to be released manually.

12. In a linotype-machine, in combination, the vertically-movable assembling-elevator, its lever and lever-shaft, a friction-disk, power-driven, adapted to actuate said elevator, a forked lever spring-actuated tending to hold the friction-disk in action, a rod adapted to overpower the forked lever actuated by a lug carried on the assembling-elevator lever, a key-lever adapted to automatically hold the rod in overpowering position and to be released manually.

13. In a linotype-machine, in combination, the vertically-movable assembling-elevator, its lever and lever-shaft, a friction-disk, power-driven, applied to said shaft, a forked

lever, spring-actuated, tending to hold the friction-disk in action, a rod adapted to overpower the forked lever actuated by a lug carried on the assembling-elevator lever, a key-lever adapted to automatically hold the rod in overpowering position and to be released manually.

14. In a linotype-machine, in combination with the vertically-movable assembling-elevator and power-driven, separable, spring-tensioning devices for raising same, a rod adapted to disconnect the power and devices adapted to control the rod.

15. In a linotype-machine, in combination with the assembling-elevator, and mechanically-actuated operating mechanism therefor, a rod actuated by a moving part of the machine and adapted to periodically disconnect said operating mechanism.

16. In a linotype-machine, in combination, the assembling-elevator, means for raising the same, the line-delivery-carriage shaft, and mechanism actuated by said shaft to periodically disconnect said raising means.

17. In a linotype-machine, in combination, an assembling-elevator, mechanism power-driven for raising said elevator, and mechanism actuated by a moving part of the machine adapted to connect and disconnect the raising power in time with the movements of the machine.

18. In a linotype-machine, the combination of the assembling-elevator and automatic actuating mechanism therefor driven by a constantly-rotating pulley, with automatic timing mechanism adapted to coördinate said actuating mechanism to the movements of the main machine actuated by a moving part thereof.

19. In a linotype-machine, in combination, the vertically-movable assembling-elevator with its lever and shaft, the line-delivery carriage and its shaft adapted to be started automatically by each upward movement of said elevator, mechanism power-driven for raising said elevator, means for holding said raising means out of action and means for automatically releasing same actuated by the line-delivery-carriage shaft and operated in time therewith, whereby the raising of the elevator releases the line-delivery carriage and the reciprocation of the line-delivery-carriage mechanism releases the elevator-raising mechanism, thus making the machine constant-running.

20. In a linotype-machine, in combination, an assembling-elevator, elevator-raising mechanism, two means for holding said raising means out of engagement and means for overpowering said two means successively.

21. In a linotype-machine, in combination with a vertically-movable assembling-elevator and power mechanism for operating same, double connecting and disconnecting means for said power mechanism, one actuated au-

tomatically by a moving part of the machine, the other operated manually to connect and automatically to disconnect.

22. In a linotype-machine, in combination, the vertically-movable assembling-elevator, mechanism adapted to raise said elevator periodically disconnected by two independent mechanisms, one thereof released by mechanism actuated by a moving part of the machine, the other manually.

23. In a linotype-machine, in combination, the vertically-movable assembling-elevator, its lever and lever-shaft, a friction-disk applied to said lever-shaft power-driven and spring-tensioned, a rod retained by a key-lever in position to hold the friction-disk apart, and actuated by a moving part of the machine to periodically overpower the last-named, whereby the friction-disk when said key-lever is operated remains disconnected until said second-mentioned rod also releases it, or unless it has already released it, and then raises the elevator.

24. In a linotype-machine, in combination, the vertically-movable assembling-elevator, mechanism adapted to raise said elevator, two rods adapted to periodically disconnect said raising mechanism, one operated by springs strong enough to disconnect said raising mechanism and to hold it disconnected and actuated to periodically release it by a moving part of the machine, the other rod actuated to disconnect said raising mechanism by a lug on the assembling-elevator lever, a key-lever adapted to automatically hold the last-mentioned rod in disconnecting position and to manually release it.

25. In a linotype-machine, in combination, the vertically-movable assembling-elevator, mechanism adapted to raise said elevator periodically disconnected by two independent mechanisms, one thereof released by mechanism actuated by a moving part of the machine, the other manually, and means for fastening the latter out of action.

26. In a linotype-machine, in combination, the vertically-movable assembling-elevator, mechanism adapted to raise said elevator, mechanism for automatically disconnecting said raising mechanism timed to act at the moment said elevator arrives up, mechanism for automatically holding and manually releasing the last-named mechanism, means for locking the last-named mechanism out of action, means actuated by a moving part of the machine to disconnect and connect said raising mechanism in time to the movements of the machine.

27. In a linotype-machine, in combination, the assembling-elevator, its lever and lever-shaft, a friction-disk power-driven applied on said lever-shaft adapted when in action to raise said elevator, a lever spring-actuated tending constantly to hold said friction-disk in action, two means for overpowering said

lever, one operated through intermediate mechanism by a moving part of the machine, the other actuated by a lug on said elevator-lever, a key-lever adapted to hold the last 5 named in active position or let it go, means to lock the key out of action.

28. In a linotype-machine, in combination, the assembling-elevator, mechanism for raising and dropping the same, the line-delivery-carriage shaft and mechanism intermediate between the line-delivery-carriage shaft and said elevator actuated by the former to drop the latter at the moment when the matrix-line has passed clear of said assembling-elevator.

29. In a linotype-machine, in combination, the assembling-elevator adapted to have a reciprocating motion, means tending normally to latch said elevator up, the line-delivery-carriage shaft, a lug on said shaft and means actuated by said lug to throw out said latching mechanism at the time when the matrix-line has passed out of the elevator.

30. In a linotype-machine, in combination, the reciprocating assembling-elevator, a latch adapted to latch it up, means for holding said latch in yielding engagement with said elevator, the line-delivery-carriage shaft, a cam on said shaft, means actuated 30 by said cam to disengage said latch, whereby the latch is disengaged in time to the movements of the line-delivery-carriage shaft.

31. In a linotype-machine, in combination, the assembling-elevator, automatic elevator-raising mechanism, automatic means for disconnecting the latter allowing the former to

fall by gravity, and automatic means for timing both the going up and the return of the elevator.

32. In a linotype-machine, an attachment 40 for operating the assembling-elevator comprising separable connections with the power-driven parts of the machine adapted to raise the elevator, devices to disconnect the power when raised, and devices to reconnect 45 it, operating substantially as described.

33. In a linotype-machine, in combination with a movable assembling-elevator, throw-out mechanism adapted when connected up to raise said elevator, and when disconnected 50 to let it fall, and means for connecting and disconnecting said raising mechanism.

34. In a linotype-machine, in combination with a movable assembling-elevator, means for raising same and throw-out mechanism 55 for said raising means adapted to act after the elevator has been raised and in time to permit its return by gravity.

35. In a linotype-machine, in combination with the movable assembling-elevator, mechanism adapted when connected up to raise said elevator and when disconnected to let it fall, and means for connecting and disconnecting said raising mechanism.

In testimony whereof I hereto affix my 65 signature, in presence of two witnesses, this 22d day of July, 1903.

CHARLES T. LIBBY.

In presence of—

FRANK H. HASKILL,
FLORENCE I. THOMPSON.
